REFRIGERATION

Filed Sept. 5, 1931

FIG. 1.

FIG. 2.

Inventor:

GORDON VARNEY

By Ernest E. Harmon

Attorney

UNITED STATES PATENT OFFICE

2,015,168

REFRIGERATION

Gordon Varney, Bradenton, Fla.

Application September 5, 1931, Serial No. 561,457

14 Claims. (Cl. 62—104)

This invention relates, in general, to the art of refrigeration, and more particularly to that phase of refrigeration known as "quick freezing", the objects to be frozen being, usually, either articles 5 subject to rapid deterioration in the absence of low temperatures or articles which would suffer disintegration, chemically or physically, if frozen by a prolonged process. Processes intimately related to the one disclosed in this application have been disclosed in my co-pending applications, Serial Number 542,503, filed June 6, 1931; Serial Number 544,802, filed June 13, 1931.

It is an object of this invention to provide a method of, and an apparatus for, such refrigeration in which a refrigeration tube is provided with a relatively shallow body of heat conductive fluid in its lower portion to provide flotation for the objects to be frozen and to provide for an intimate heat exchange contact which is free from 20 insulation, due to frosting.

Another object of my invention is to supply such a fluid in a refrigerating tube in the interests of providing a certain degree of flotation and a lessening of frictional resistance to the passage 25 of an article, to be refrigerated, through said tube.

It is a further object of my invention to provide as a carrier means, for progressive refrigeration, floatable on such liquid, a carrier which, in itself, is adaptable for use in wrapping the article to be 30 refrigerated.

Other objects of my invention will be found in the accompanying specification and claims, and will be disclosed in the accompanying drawing, in which:

Figure 1 is a schematic showing in a vertical cross-section taken longitudinally of my device.

Figure 2 is a transverse cross-section of the structure shown in Figure 1 taken along the line 2—2 of Figure 1.

Referring now with greater particularity to the drawing, it will be seen that my device is comprised as follows. A suitable refrigeration chamber 1 is provided with a refrigerant tube 2 having inlet and outlet conduits 3 and 4, respectively, 40 for the ingress and egress of refrigerant. Surrounding the tube 2, within the chamber 1, is a fluid 5 of relatively high specific gravity and high heat conductivity, the fluid 5 being supplied in sufficient quantity to attain a level of shallow 45 depth above the upper surface of the tube 2. The inner walls of the chamber 1 are formed with projections 6, curved as shown, and reaching approximately to the adjacent upper covers of the tube 2.

At 7 I have shown a roll of "Cellophane" 8, or

some such similar flexible material, which is adapted to act as a carrier for the packages 8 to be frozen. The rollers 9, 10, 11 and 12 provide for feeding the "Cellophane" from the roller 8. A spray nozzle 13 is provided for cleaning the "Cellophane" of the fluid 5 and wipers 14 are provided to supplement this cleaning process. Leaving the roller 12, the "Cellophane" falls onto table 15 together with the package 16. The "Cellophane" strip is then cut to the desired dimensions 10 and used as a wrapper for the package 16.

From the foregoing it will be seen that my device operates as follows. Under the influence of the action of rollers 9, 10, 11 and 12 the sheet of "Cellophane", or other similar material, is fed 15 from the roll 7 through the chamber 1. The curved projections 6 cause the "Cellophane" to be curved upwardly at its lateral edges. There is a sufficient amount of liquid 5 to insure that the package 16 is wholly, or almost entirely, floated 20 by said liquid, and that the contact, if any, between the upper surface of the tube 2 and the "Cellophane" would be such as to provide a negligible frictional resistance. As the "Cellophane" strip emerges, with its package from the chamber 1, its lower surface is subjected to the cleansing action of the spray 13 and the wipers 14. The packages 16 fall onto table 15 and the "Cellophane" 8 emerging from the rollers, is cut to appropriate sizes and used as a wrapper for the 30 packages frozen.

It will be seen that I have thus provided a refrigeration chamber having a refrigeration tube surrounded by a flotation fluid, the liquid and projections of the chamber 1 forming a curved 35 guide for the "Cellophane" carrier. This curved guide is to prevent contact of the article to be refrigerated with the liquid 5. The carrier serves the dual purpose of conveying the packages through the refrigeration chamber and of serving as a wrapper for the refrigerated product. The liquid 5 serves as a flotation and friction reducing means as well as a heat conductive medium. The fluid 5 is substantially static within the chamber 1.

Having thus described my invention, I claim:

1. As a refrigeration apparatus, a refrigerating chamber, a film of substantially static heat conductive liquid filling the base of said chamber, a carrier passing through said chamber and contacting with said liquid.

2. As a refrigeration apparatus, a refrigeration chamber, a refrigerating tube extending throughout the length of said chamber, a carrier positioned in said chamber above said tube, and a film 55

of heat conductive liquid means thermally connecting said tube and said carrier.

3. As a refrigeration apparatus, a refrigeration chamber, a refrigeration tube extending throughout the length of said chamber, a carrier positioned in said chamber and above said tube, and a film of heat conductive fluid wetting the upper surface of said tube and the lower surface of said carrier.

10 4. In a refrigeration apparatus, a refrigerated tube, a carrier extending through said tube for conveying an article to be refrigerated, the lower portion of said tube being filled with a substantially static liquid of high heat conductivity contacting with said carrier, the bottom of said carrier and the adjacent surface of said refrigerated tube having interposed therebetween a thin film of said fluid.

20 5. In a refrigeration apparatus, a refrigerated tube and a substantially flat carrier of moisture-proof flexible material passing therethrough for conveying articles to be refrigerated, the lower portion of said tube being filled with a liquid, said carrier being adapted to be wrapped about said article when the process of refrigeration is complete so as to form a container for said article, said carrier contacting with the surface of said liquid.

30 6. In a refrigeration apparatus, a refrigerated tube and a substantially flat carrier of moisture-proof flexible material passing therethrough for conveying articles to be refrigerated, the lower portion of said tube being filled with a liquid of high heat conductive properties, said carrier being adapted to be wrapped about said articles when the process of refrigeration is complete so as to form a container for said article, said carrier contacting with the surface of said liquid.

40 7. In a refrigeration apparatus, a refrigerated tube, a substantially flat carrier of moisture-proof flexible material passing therethrough for conveying articles to be refrigerated, the lower portion of said tube being filled with a liquid of high heat conductivity contacting with said carrier, said carrier being adapted to be wrapped about said article when the process of refrigeration is complete so as to form a container for said article, said carrier contacting with the surface of said liquid.

50 8. In a refrigeration apparatus, a refrigeration chamber, means for providing and maintaining a film of substantially static heat conductive liquid filling the base of said chamber and a carrier passing through said chamber and contacting with said liquid while the articles to be refrigerated are in thermal contact therewith.

55 9. In a refrigeration apparatus, a refrigeration chamber, means for providing and maintaining a substantially static heat conductive liquid filling

the base of said chamber and a substantially flat carrier of moisture-proof flexible material passing through said chamber and contacting with said liquid while the articles to be refrigerated are in thermal contact therewith, said carrier being adapted to be wrapped about the articles to be refrigerated when the refrigeration process is completed so as to form a container for said article.

10 10. In a refrigeration apparatus, a refrigerating chamber, means for refrigerating said chamber, means for providing and maintaining a film of heat conductive liquid filling the base of said chamber, means for refrigerating said liquid and a carrier passing through said chamber and contacting with said liquid while the articles to be refrigerated are in thermal contact therewith.

15 11. In a refrigeration apparatus, a refrigerating chamber, means for refrigerating said chamber, a heat conductive liquid filling the base of said chamber and a substantially flat carrier of moisture-proof flexible material passing through said chamber and contacting with said liquid, said carrier being adapted to be wrapped about the articles to be refrigerated when their refrigeration process is completed so as to form a container for said article, said carrier contacting at its base with said liquid.

20 12. In a refrigeration apparatus, a refrigerating chamber, means for providing and maintaining a film of substantially heat conductive liquid filling the base of said chamber and a carrier passing through said chamber and contacting with said liquid.

25 13. In a refrigeration apparatus, a refrigerating chamber and substantially static heat conductive liquid filling the base of said chamber and a substantially flat carrier of moisture-proof flexible material passing through said chamber and contacting with said liquid while the articles to be refrigerated are in contact therewith, said carrier being adapted to be wrapped about the articles to be refrigerated when the refrigeration process is completed so as to form a container for said article.

30 14. In a refrigeration apparatus, a refrigerated tube, a substantially flat carrier of moisture-proof flexible material extending through said tube for conveying an article to be refrigerated, the lower portion of said tube being filled with a substantially static liquid of high heat conductivity contacting with said carrier, the bottom of said carrier and the adjacent surface of said refrigerated tube having interposed therebetween a thin film of said fluid, said carrier adapted to be wrapped about said article when the process of refrigeration is complete so as to form a container for said article.

GORDON VARNEY.
